UNITED STATES PATENT OFFICE.

JOHN A. LAMONT, OF CHICAGO, ILLINOIS, ASSIGNOR TO AMERICAN STEEL FOUNDRIES, OF CHICAGO, ILLINOIS, A CORPORATION OF NEW JERSEY.

RAILWAY-CAR TRUCK.

Application filed July 18, 1921. Serial No. 485,430.

To all whom it may concern:

Be it known that I, JOHN A. LAMONT, a citizen of the United States, residing at Chicago, in the county of Cook and State 5 of Illinois, have invented certain new and useful Improvements in Railway-Car Trucks, of which the following is a specification.

This invention relates to railway car 10 trucks and more particularly to six-wheel equalizing trucks.

One object of the invention is to provide a simple and improved equalizing arrangement in which the number of parts is reduced without sacrificing operative efficiency.

Another object is to support the load on the journal boxes in a manner to prevent said boxes from tilting and to reduce wear 20 on the box guides.

Another object is to load the equalizing beams in a manner to maintain them in a centrally balanced position or to quickly restore them to such position if they are 25 moved therefrom.

Another object is to provide an equalizing arrangement adapted to meet the various requirements for successful commercial operation.

These and other objects are accomplished 30 by means of the arrangement disclosed on the accompanying sheets of drawings, in which—

Figure 1 is a fragmentary side elevation, 35 parts being in section, of a railway car truck embodying my invention;

Figure 2 is a fragmentary top plan view of one of the side frames and associated parts of the truck;

Figure 3 is a sectional view taken in the 40 plane of line 3—3 of Figure 1; and

Figure 4 is a sectional view taken in the planes of the irregular line 4—4 of Figure 1.

The various novel features of my invention will be apparent from the following description and drawings and will be particularly pointed out in the appended claims.

Referring to the figures of the drawings it will be noted that I have described my 50 invention in connection with a six-wheel equalizing truck including a side frame 10 having a central journal box opening 11 and end journal box openings 12, only one

of which is shown. The side frame also has openings 13, only one of which is shown 55 intermediate the journal box openings 11 and 12 for the reception of bolster members 14 which rest upon and are supported by equalizing levers 15. The outer end of each of said equalizing levers is pivotally mounted 60 on a pin 16, the pin in each case being supported in the side walls 32 and 33 of the frame 10. Each of the equalizing levers is in the form of a gooseneck, the intermediate portion being a curved low portion 65 upon which the associated bolster member is supported, the outer portion curving upwardly and supported, as stated above, by the pin 16, and the inner portion curving upwardly into a vertical portion and terminating in a longitudinally extending nose 70 17 which rests upon its associated end 18 of an equalizing beam 19 which is pivotally mounted at its middle portion upon a pin 20. This pin 20 is supported in a groove 75 at the middle of a spring cap 21 which bridges the coiled springs 22 supported upon laterally extending brackets 23 of the intermediate journal box 24. The journal receiving portion 25 of the journal box is provided with a U-shaped steel wearing plate 80 26 and is relatively vertically movable in the intermediate pocket or journal box opening 11.

The spring cap 21 has downwardly extending portions 27 at its ends which are guided in relatively vertical movements with respect to the side frame by shoulders or walls 28 and 29 formed integrally with the side frame. The walls 28 house or embrace 90 the major portion of the associated coiled springs 22. In addition to having the downwardly extending portions 27, the spring cap also has upwardly extending end wall portions 30 which cooperate particularly 95 with the upper portions of the shoulders or walls 29. The spring cap also has upwardly extending side wall portions 31 (see Figure 3) between which the equalizing beam 19 is mounted, whereby the beam is 100 maintained against lateral displacement. The spring cap 21 in turn is housed within the side walls 32 and 33 of the side frame at the section shown in Figure 3. In the same section it will be noted that the journal box 24 has upstanding side walls 34 and 105

35 which limit the lateral movement between the journal box and the associated side frame.

By providing equalizing levers of the 5 type shown wherein the inner portions extend vertically upwardly and the longitudinally extending noses extend through the openings 36 and 37 in the walls 29 and 30 respectively, and rest upon the ends of the 10 equalizing beam 19, all hanger connections between the equalizing beam and equalizing levers as shown in some of my earlier patents, for example, Patent No. 1,377,704, granted May 10, 1921, are eliminated. It 15 will be noted also that the load is transmitted through the equalizing levers and associated parts to the brackets 23 of the journal box 24 at a point below the center line of the axle. The load thus applied has a 20 natural tendency to hang vertically and does not require that the journal box have the same amount of guiding as when the load is applied above the journal. This lessens the tendency of the journal box to tip one 25 way or the other, and also reduces the wear between the journal box and its associated guides.

In this same connection it will be noted that the equalizing levers 15 engage the ends 30 of the equalizing beam 19 at points below the pivot point 20 of the equalizing beam for maintaining said equalizing beam in its centrally balanced position. If, for any reason, the equalizing beam 19 should swing 35 about its pivot, the lowered end will have its lever arm at that side reduced and the opposite end in moving upwardly will have its lever arm lengthened which creates an immediate tendency to counterbalance or for 40 the equalizing beam to again assume its normal horizontal position.

It will be noted further that a straight line drawn between the pivot pins 16 and 20 for all practical purposes substantially 45 includes the bearing point 38 between the nose 17 and end 18 of the equalizing lever 19. In other words, the points 16, 38 and 20 lie substantially in the same straight line. In this way relative movement between the bearing 50 surfaces of the nose 17 and the associated end 18 of the equalizing beam 19 is reduced to a minimum, and likewise the wear between said parts is reduced to a minimum.

55 By means of the arrangement disclosed the loads equalize even under the most adverse track conditions. For example, if the middle pair of wheels should fall below the plane of the outer pair of wheels, such as on 60 a switch-back, the inner ends of the equalizing levers 15, the equalizing beam 19 and the spring cap 21 would follow the journal box in its downward movement, the side frame remaining stationary and conversely 65 if the middle pair of wheels is caused to rise

the associated parts mentioned, with the exception of the side frame, would rise also, the spring cap 21 being guided in its relative vertical movement with respect to the side frame by the side frame walls or 70 shoulders 28 and 29.

It is my intention to cover all modifications of the invention falling within the spirit and scope of the following claims.

I claim:

1. In a six-wheel truck, the combination of an intermediate journal box, resilient means carried thereby, an equalizing beam from which loads are transmitted to said journal box through said resilient means, and equalizing levers having direct engagement with said equalizing beam for transmitting loads thereto. 75

2. In a six-wheel truck, the combination of an intermediate journal box, resilient means carried thereby, an equalizing beam from which loads are transmitted to said journal box through said resilient means, equalizing levers having direct engagement with said equalizing beam for transmitting 80 loads thereto, and bolster members mounted directly on said equalizing levers. 85

3. In a six-wheel truck, the combination of an intermediate journal box, springs associated therewith, a spring cap mounted on 90 said springs, an equalizing beam mounted on said spring cap, and equalizing levers directly engaging said equalizing beam whereby loads are transmitted through said equalizing beam, cap and springs to said 95 journal box.

4. In a six-wheel truck, a pivotally mounted equalizing beam associated with an intermediate journal box, an equalizing lever pivotally supported at one of its points and 100 engaging said equalizing beam, the point of engagement between said equalizing beam and equalizing lever being in substantially a straight line drawn between pivot points of said lever and beam whereby the relative movement between the engaging surfaces of said equalizing lever and beam and the wear occasioned thereby are reduced to a minimum. 110

5. In a six-wheel truck, a pivotally mounted equalizing beam associated with an intermediate journal box, and equalizing levers directly engaging said equalizing beam at a level below the pivotal point of said beam whereby the beam has a tendency to remain 115 in its normal horizontal position or is returned to such position if it is moved therefrom.

6. In a six-wheel truck, a side frame, an intermediate journal box having a relatively 125 vertical movement with respect thereto, spring means mounted on said journal box, a cap supported by said spring means, an equalizing beam pivotally supported on said cap, and equalizing levers engaging said 130

equalizing beam transmitting loads through said beam, cap and spring means to said journal box, said side frame and cap having engaging portions whereby relative movements therebetween are guided.

7. In a six-wheel truck, a side frame, an intermediate journal box having relatively vertical movement with respect thereto, spring means mounted on said journal box, a cap supported by said spring means, an equalizing beam pivotally supported on said cap, and equalizing levers engaging said equalizing beam transmitting loads through said beam, cap and spring means to said journal box, said side frame and cap having engaging portions whereby relative movements therebetween are guided, the inner ends of said equalizing levers extending through openings in said guiding portions for permitting such relative movements.

8. In a six-wheel truck, a side frame having a journal box opening and a plurality of guide portions at each side thereof, a journal box mounted in said opening, resil-

ient means mounted on said journal box, a spring cap bridging said resilient means and being guided in its relative movement with respect to said side frame by said guide portions, an equalizing beam mounted on said cap, and equalizing levers operatively connected to said equalizing beam.

9. In a six-wheel truck, an intermediate journal box, springs carried at the opposite sides thereof and supported at a point below the center line of the journal, a spring cap bridging said springs, an equalizing beam pivotally mounted on said cap, and equalizing levers operatively connected to said equalizing beam whereby loads are transmitted through said beam, cap and springs to said journal box, said springs being supported on the journal box at a point below the center line of the journal to overcome any tendency for the journal box to tip on one side or the other.

Signed at Chicago, Illinois, this 6th day of July, 1921.

JOHN A. LAMONT.
